HAND GUN

Philip R. Lichtman, 35 Lee St., Cambridge, Mass. 02173

Filed Nov. 5, 1973, Ser. No. 412,727

Term of patent 14 years

Int. Cl. D22—01

U.S. Cl. D22—1

F/G. 3

F/G. 1

F/G. 2

FIG. 5

FIG. 4

FIG. 6

FIG. 1 is a side view in elevation of a hand gun embodying my new design;

FIG. 2 is a rear view of the same hand gun;

FIG. 3 is a front view of the same hand gun;

FIG. 4 is an opposite side view in elevation of the same hand gun;

FIG. 5 is a plan view of the same hand gun; and

FIG. 6 is a bottom view of the same hand gun.

I claim:

The ornamental design for a hand gun, substantially as shown and described.
